UNITED STATES PATENT OFFICE

2,323,849
HEATING AND HUMIDIFYING SYSTEM

Warren E. Schnoes, Chicago, Ill.

Application June 12, 1941, Serial No. 397,762

7 Claims. (Cl. 237—10)

This invention relates to heating systems, and has reference more specifically to steam heating systems having a compressed air automatic control. The invention further relates to a heating and humidification system in which compressed air is used as a means for vaporizing water for humidification purposes.

In the past, steam heating systems through the use of radiators have been far from efficient in maintaining a selective uniform temperature and humidity in a zone and have been wasteful in the use of fuel. The installation, operating and maintenance costs have also been unduly high.

An object of the invention therefore is to provide a steam heating system which will operate efficiently in attaining desired temperatures in a zone with the use of a minimum amount of fuel.

Another object of the invention is to provide a steam heating system in which compressed air is used for controlling the flow of steam to the radiators.

A further object of the invention is to provide a compressed air controlled steam heating system with provision for the vaporization of water of condensation for humidification purposes.

A still further object of the invention is to provide a heating and humidification system which will be low in installation, operating and maintenance costs; also to improve heating and humidification systems in other respects herein-after specified and claimed.

Reference is to be had to the accompanying drawings forming a part of this specification, in which

Fig. 1 is a piping diagram of a multiple zone heating and humidification system.

Fig. 2 is an elevation of a single zone heating and humidification system, and

Fig. 3 is an enlarged sectional elevation through the humidification system taken on line 3—3 of Fig. 2.

Referring to the drawings by numerals, a heating zone, such as an apartment, may consist of a number of radiators 10, 11 and 12, each equipped with steam risers 13, 14 and 15, respectively, all of which are supplied with steam from a single boiler. The radiator 12 will generally be larger than the radiators 10 and 11 and will be positioned in the room where the most heat is required. The radiator 12 will also be equipped with a thermostat 16 which is connected in parallel with a room thermostat 17 by lines 18. A compressed air supply pipe 19 leads from an air compressor and is provided with a

5 solenoid valve 20 of standard construction which is connected by lines 21 to thermostat 17 and lines 18. This valve 20 is normally closed and opens only on the passage of current from a battery 21a. Water drainage pipes 22, 23 and 24 lead from the bottom of each of the radiators 10, 11 and 12 through drainage valves 25, 26 and 27 respectively, said pipes 22, 23 and 24 being connected by manifold 29 to a water trap 30. 10 A water return pipe 31 leads the water of condensation back to the steam boiler. Check valves 33, 34 and 35 connect the steam risers 13, 14, and 15 to the radiators 10, 11 and 12 respectively so as to prevent back-flow of compressor air from 15 the radiators into the steam risers. Each of the valves 33, 34 and 35 is provided with a set screw so that heat in a room may be shut off if desired. The drainage valves 25, 26 and 27 permit the passage of water of condensation and compressed air 20 from the bottom of the radiators but prevent the passage of steam therethrough.

In the form of invention shown in Fig. 1, a 25 multiple zone heating system is illustrated, such as two apartments, one above the other. The piping diagram is to illustrate a combination of elements similar to that shown in Fig. 2. The radiators 37, 38 and 39 in the upper zone or apartment are connected in parallel with radiators 40, 41 and 42 in the lower zone or apartment. There is a separate compressed air valve 43 and 44 and a separate trap 45 and 46 for each apartment. A single manifold 47 returns the hot water of condensation from both traps 45 and 46 back to the boiler. A single air supply line 35 48 supplies the valves 43 and 44.

For the purpose of humidification, a branch air line 49 leads from the water drainage line 24 to a point underneath the radiator 12 where it is provided with an upwardly directed nozzle 50. 40 A water pan 51 extends under the radiator 12 about the nozzle 50 and a baffle 52 with downwardly extending flanges 53 extends between the walls of the pan 51 over the nozzle 50 to reduce the noise of the incoming air and spread the air more uniformly over the area of the radiator 12. A felt 54 extends over the baffle 52 and upper surface of the pan 51 so as to remain moist and prevent any actual spray of water from passing upwardly from the nozzle 50. An overflow pipe 55 connects one end of pan 51 at the desired level to the drain to prevent the pan 51 from overflowing with water of condensation. The damp air passing up through the felt 54 flows around the radiator 12 where it is warmed up and its relative humidity lowered and its temperature

raised considerably above the dew point, thus precluding the possibility of any condensation forming in the room.

In operation, when heat is desired, the steam pressure will be greater in the risers 13, 14 and 15 than air pressure in radiators 10, 11, and 12, thus opening check valves 33, 34 and 35. Steam thus flows into radiators 10, 11 and 12 and forces the air and water of condensation in said radiators, out through drainage valves 25, 26 and 27. Some of the water and all of the air flows out through nozzle 50 below baffle 52 into pan 51. The air and considerable water vapor passes upwardly through felt 54 around the control or master radiator 12 where the relative humidity of the air is raised by absorbing heat from said radiator. When the temperature of the radiator 12 reaches the temperature at which it operates at maximum efficiency, thermostat 16 among the heating sections of control radiator 12, opens solenoid valve 20 so that compressed air enters the radiators 10, 11 and 12 through drainage valves 25, 26 and 27 respectively and shuts off the flow of steam into said radiators through risers 13, 14, 15. Air is prevented from flowing into risers 13, 14 and 15 by check valves 33, 34 and 35. All of the air which passes valve 20 eventually flows out through nozzle 50 to supply fresh, warm, humidified air to the zone heated by the radiators 10, 11 and 12. Room thermostat 17 also acts independently of thermostat 16 when zone temperature exceeds a predetermined point, to actuate solenoid valve 20 and introduce air into the radiators to check the flow of steam. The excessive water of condensation flows through trap 30 back to the boiler. Any excess water collecting in pan 51 overflows through the pipe 55 to a drain.

I would state in conclusion that while the examples illustrated constitute practical embodiments of my invention, I do not wish to limit myself precisely to these details, since manifestly the same may be considerably varied without departing from the spirit of the invention as defined in the appended claims.

Having thus described my invention, I claim as new and desire to secure by Letters Patent:

1. In a heating and humidifying system, a steam radiator, means for supplying steam to said radiator, means for directing compressed air into said radiator at a higher pressure than said steam so as to check the flow of steam into said radiator, thermostat means responsive to both room and radiator temperature for controlling the flow of compressed air into said radiator, and a nozzle and spreader baffle for causing said compressed air to vaporize a portion of

water of condensation outside of said radiator for humidification of the air in said room.

2. In a heating and humidifying system, a steam radiator, means for supplying steam to said radiator in one direction, means for directing compressed air at a higher pressure than said steam into said radiator in a direction opposite to the flow of steam so as to check the flow of steam, a trap to permit water of condensation but not air to flow from said radiator, thermostat means responsive to both room and radiator temperature to control the flow of air to said radiator, and a nozzle and spreader baffle to cause said compressed air to vaporize a portion of water of condensation outside of said radiator for humidification of the air in said room.

3. In a heating and humidifying system, a steam radiator, means for supplying steam to said radiator, means for introducing compressed air into said radiator to check the flow of steam thereto, a water pan, a felt over said water pan, and a conduit for withdrawing condensate water from said radiator, a restricted conduit leading from said condensate conduit, and a nozzle on the end of said restricted conduit for causing said compressed air to vaporize a portion of water of condensation from said radiator between said pan and said felt.

4. A system as described in claim 3 characterized by a baffle in said pan below said felt to act as a spreader for said water vapor.

5. A system as described in claim 3 characterized by an overflow drain associated with said pan to limit the height of water in said pan.

6. In a heating system, a plurality of radiators for heating a zone, means for supplying steam to each of said radiators, thermostatically operated means responsive to both radiator and room temperature for simultaneously introducing compressed air into each of said radiators to check the flow of steam thereto, and a nozzle and spreader baffle for causing said compressed air to vaporize water of condensation from a radiator for increasing the humidity in said zone.

7. In a heating and humidifying system, a steam radiator, means for supplying steam to said radiator, means for introducing compressed air into said radiator to check the flow of steam to said radiator, means responsive to both radiator and room temperature for thermostatically controlling the flow of air to said radiator, a nozzle and spreader baffle for causing said compressed air to vaporize a portion of the water of condensation outside of said radiator for the humidification of the air in said room, said nozzle being arranged to direct said water vapor and air mixture adjacent said radiator to raise the relative humidity of said air.

WARREN E. SCHNOES.
